DESIGN FOR A LINK CHAIN FOR A BRACELET OR SIMILAR ARTICLE

Nathan Tall, Los Angeles, Calif.

Application March 25, 1946, Serial No. 130,867

Term of patent 7 years

(Cl. D45—4)

To all whom it may concern:

Be it known that I, Nathan Tall, a citizen of the United States of America and a resident of the city of Los Angeles, in the county of Los Angeles and State of California, have invented a new, original, and ornamental Design for a Link Chain for a Bracelet or Similar Article, of which the following is a specification, reference being had to the accompanying drawing, forming part thereof.

In the drawings:

Figure 1 is a top perspective view of a link chain for a bracelet or similar article, showing my new design.

Figure 2 is a sectional view taken substantially along the line 2—2 of Figure 1.

I claim:

The ornamental design for a link chain for a bracelet or similar article, substantially as shown.

NATHAN TALL.
